WIRE CABLE

Charles C. Sunderland, New Brunswick, N. J.,
assignor to John A. Roebling's Sons Company,
Trenton, N. J., a corporation of New Jersey

Application May 24, 1932, Serial No. 613,153

5 Claims. (Cl. 14—22)

This invention relates to wire cables formed of a group of parallel wire strands, such as are used for bridge cables and other heavy load work.

In the making of parallel strand cables heretofore, it has been common practice to build up the cable to a cross-section roughly hexagonal. The cross-section is then filled out to circular by means of large fillers and the assembly wrapped with wire. An objection to this construction is that if the fillers are made of wood or other inert material, the fillers are apt to deteriorate and the wrapping wire may become loosened, in time, by being embedded in the fillers, so that eventually moisture can penetrate to the strands. If the wires are laid up helically in the strands, the moisture will penetrate through the strands and the difficulty is increased. On the other hand, the cost of metal fillers of this type is almost prohibitive, due to the excessive weight of metal.

20 It is an object of the present invention to provide a wire cable of the parallel strand type, such that danger of moisture penetrating the strands is practically eliminated and without excessive cost or weight.

25 With this general object and others in view, the invention consists in the features, combinations, details of construction and arrangements of parts that will first be described in connection with the accompanying drawings and then more particularly pointed out.

30 In the drawings:

Figure 1 is a plan view, with parts broken away and removed, of a wire rope or cable constructed in accordance with the invention in its preferred form.

35 Figure 2 is a sectional view (enlarged) taken on the line 2—2 of Figure 1;

Figure 3 is an enlarged longitudinal sectional view;

40 Figures 4 and 5 are fragmentary views showing enlargements of parts of Fig. 2; and

Figures 6 and 7 are similar views showing a modified construction.

45 Referring to the drawings, the cable here illustrated as an example, such as a main bridge cable, comprises a plurality of parallel major strands 10. Each of these major strands is formed of helically laid wires or wire strands 11, such wire strands being formed of a plurality of 50 wires laid up helically or parallel. The major strands 10 are built up, as appears in Fig. 2, to a roughly hexagonal cross-section. At the corners of the hexagon are supplemental strands 14, of smaller diameter, that serve to round out the 55 cross-section to a shape roughly circular.

The invention in its entirety includes an inner protective winding of metallic tape and a substantially uninterrupted cylindrical support therefor.

5 While the supporting means may vary, it may conveniently be accomplished by means of light, hollow metallic fillers. In the embodiment illustrated as an example in Figs. 1 to 5, the fillers are so constructed that they envelope completely the circumference of the cable, and, in themselves, give a substantially uninterrupted support for the wrapping later described. The complete filling support is made up of a plurality of individual fillers, alternating in specific construction to accord with the cable strands. Thus, there 10 are six what may be termed side fillers for the sides of the rough hexagon formed by cable strands 10 and six what may be termed corner fillers alternating with the side fillers.

15 Each side filler (Figs. 2 and 4) comprises a hollow metallic structure having, in cross-section, an arcuate outer wall 16. Opposite the center of this outer wall is an inner arcuate wall 17 that embraces one of the cable strands 10. Between these two walls the filler has arcuate connecting 20 walls 18, 19, that partially embrace the adjacent strands 10. The inner wall 17 is formed with a strengthening and supporting rib 20.

25 Each corner filler (Figs. 2 and 5) comprises a hollow metallic structure having an outer arcuate 30 wall 21, an inner arcuate wall 22 embracing a supplemental strand 14 and connecting arcuate walls 23, 24. The inner wall 22 is self-supporting on the outer wall 21. The end wall 24 of each corner filler forms, in effect, a continuation of the 35 end wall 18 of the adjacent side filler in embracing one cable strand 10 and a like relation exists between end walls 23 and 19.

30 The outer wall of each side filler forms, in effect, a continuation of the outer wall of the 40 adjacent corner filler, so that the several outer walls form a substantially uninterrupted cylindrical support completely enveloping the cable, as appears in Figs. 1 and 2.

45 The inner protective wrapping here shown as an example comprises a helically wound continuous metallic tape 27, e. g., of zinc. This tape is so dimensioned and so wound that each turn overlaps the preceding turn about two-thirds of the tape width. Thus, as illustrated more clearly 50 in Fig. 3, which shows three turns, a, b and c, there is a triple overlap that gives three thicknesses of zinc covering along the cable.

55 Wound over this protective tape is the usual outer winding of wire 28 which may be round

wire, as shown, or of other suitable form. As appears more clearly in Fig. 3, the outer wire winding practically seals the several laps of the tape winding and there is substantially no chance of any moisture penetrating to the cable strands. The metallic fillers are not liable to deteriorate and are light enough to avoid undue metal cost. These fillers, moreover, provide a firm unbroken support for the tape.

10. In the modification illustrated in Figs. 6 and 7, associated with the strands are reverse-hand duplicate side fillers 29 in the form of hollow metallic elements roughly triangular in cross-section, and similar reverse-hand duplicate corner fillers 30. These fillers have arcuate outer walls 31, 32, respectively, but the several outer walls are spaced one from another circumferentially. To round out a cylindrical support for the winding of protective tape, the gaps between the hollow metal fillers are closed by supplemental fillers 33 in the form of inserts of some inert material. The protective winding of metallic tape and the outer winding of wire are the same as in the embodiment first described.

25. It will be understood that, while the invention has been illustrated only in preferred forms with the cable strands formed of wire or wire strands laid up helically, and the invention is especially applicable in connection with such strands, the claims not thus limited are intended to include, also, strands formed of wire or wire strands laid up parallel, and that other modifications may be made in the constructions illustrated within the invention defined by the claims.

35. What is claimed is:

1. In a wire cable comprising a plurality of parallel strands, fillers associated with the strands, said fillers comprising metallic elements having arcuate outer walls, the several outer walls forming a substantially unbroken support enclosing said strands, an inner protective wrapping of metallic tape wound on said support in overlapping turns, and an outer sealing wrapping of wire on said tape found helically at approximately right angles to the cable with the successive wraps abutting to seal the cable.

2. A wire cable comprising a plurality of parallel strands of substantially equal size so arranged as to have a roughly polygonal outline in cross-section and a plurality of smaller strands located at the corners of said polygon, said cable having metallic fillers associated with the strands to round out a circular cross-sectional outline and a protective wrapping sealing the cable against the entrance of moisture.

3. A wire cable comprising a plurality of parallel strands laid up in a substantially polygonal group, smaller strands each partially filling the space at a corner of the polygon, preformed hollow fillers each overlaying the strands of one side of the polygon, separate preformed hollow fillers each overlaying one of the smaller corner strands and substantially closing the space between the adjacent fillers overlaying the larger strands, all of said fillers being formed with arcuate outer walls to round out the structure, and a metal covering over the fillers sealing the cable against the entrance of moisture.

4. A wire cable comprising a plurality of parallel strands laid up in a substantially polygonal group, smaller strands each partially filling the space at a corner of the polygon, preformed hollow fillers overlaying the strands of the polygon, separate preformed hollow fillers each overlaying one of the smaller corner strands and substantially closing the space between the adjacent fillers overlaying the larger strands, all of said fillers being formed with arcuate outer walls to round out the structure, and a metal covering over the fillers sealing the cable against the entrance of moisture.

5. A wire cable comprising a plurality of parallel strands of substantially equal size so arranged as to have a roughly polygonal outline in cross-section and a plurality of smaller strands located at the corners of said polygon, said cable having metallic fillers associated with the strands to round out a circular cross-sectional outline and a protective wrapping sealing the cable against the entrance of moisture.
